UNITED STATES PATENT OFFICE.

MAX MAXIK, OF NEW YORK, N. Y.

YARN-GUIDE RECIPROCATING MECHANISM.

Application filed January 17, 1923. Serial No. 613,197.

To all whom it may concern:

Be it known that I, MAX MAXIK, a citizen of the United States, and a resident of the city of New York, borough of Queens, in the county of Queens and State of New York, have invented a new and Improved Yarn-Guide Reciprocating Mechanism, of which the following is a full, clear, and exact description.

10 This invention relates to a yarn guide reciprocating mechanism for knitting machines and particularly to means used on a Tisch or similar knitting machine whereby substantially any width of cloth may be knit.

15 The object of the invention is to provide an improved construction for knitting machines of the Tisch type whereby the thread tube may be moved back and forth substantially any desired distance.

20 A further object of the invention is to provide an attachment which may be added to the ordinary knitting machine of the Tisch or similar type and set easily to knit extra wide widths of cloth.

25 A still further object, more specifically, is to provide a pawl and rack device with associated parts for multiplying the movement of the thread tube operating mechanism without increasing the friction of the various parts.

In the accompanying drawing—

30 Figure 1 is a fragmentary view of a Tisch knitting machine with an attachment embodying the invention applied thereto.

Figure 2 is an enlarged top plan view of one end of the structure shown in Figure 1.

35 Figure 3 is a sectional view through Figure 1 approximately on line 3—3, the same being on an enlarged scale.

Figure 4 is a sectional view through Figure 3 approximately on line 4—4.

40 Figure 5 is an enlarged fragmentary sectional view through Figure 1 approximately on line 5—5.

Figure 6 is a top plan view of the structure shown in Figure 5.

45 Figure 7 is an elevation of a slightly modified construction of bracket.

50 Referring to the accompanying drawing by numerals, 1 indicates the frame of a knitting machine of the Tisch type, as for instance, of the type shown in Patent No. 457,265. In this form of knitting machine, a tube bar 2 is provided which is reciprocated by suitable pins 3 and 4 and as bar

2 reciprocates motion is transmitted to the various tube plates 5. Heretofore, a toggle or lever arrangement was provided for accomplishing this result whereas in the present invention an improved arrangement is provided which eliminates to a large extent the friction found in the old device and at the same time presents a structure wherein the two plates 5 may be moved a short distance or a long distance so as to knit a narrow strip of cloth or a wide strip of cloth within the limits of the machine.

As indicated in Figure 5, the plate 5 is provided with a notch 6 for accommodating the bar 2. A clamping plate 7 is secured to the plate 5 by screws or other suitable means, said clamping plate having an apertured turned over end 8 which receives a tying member 9 for tying the plate 7 to the flexible operating member 10 which may be a strong cord or other material as preferred. The plate 5 is provided with a thread tube 11 of any usual or preferred structure which operates in the usual manner for guiding the thread as it is properly placed during the operation of the knitting machine.

The cord 10 is secured to the respective pulleys 12 and 13 and arranged to be wound thereon as the machine operates. According to the showing in Figure 1, an appreciable portion of the cord 10 has been wound on the pulley 13 whereby the plate 5' has been moved to its extreme position at the right of the machine. It will be noted that there are two plates 5 and 5' which are identical and when these two plates are used at the same time two strips of cloth are being knit simultaneously. If it is desired to knit a strip for the full width of the machine, one of these plates would be removed for instance plate 5 and the plate 5' would be caused to travel from one pulley to the other back and forth. This traveling of plate 5' is caused by the rotation of the respective pulleys 12 and 13 which are of identical construction so that the description of pulley 12 and associated parts will apply equally to pulley 13 and associated parts. As indicated in Figures 3 and 4, the pulley 12 is mounted on a shaft 14 which shaft is clamped to the bracket 15 by reason of the shoulder 16 and the clamping nut 17, said shaft passing through a suitable slot 18 whereby the shaft may be adjusted vertically to accommodate different size spur gears 19 and also, if desired, different size

pulleys 12. The bracket 15 is clamped rigidly to the tube bar 2 by any suitable means, as for instance, set screw 20 whereby it will move back and forth with this bar 5 and will carry with it shaft 14 on which the pulley 12 and spur gear 19 are mounted. The spur gear 19 is adapted to be rigidly secured to the pulley 12 by any suitable means, as for instance, by the plate 21 which 10 is secured in place by screws as indicated in Figure 3. The spur gear 19 is continually in mesh with the teeth 22 of the rack bar 23 whereby when the bracket 15 is moved by the tube bar 2 the spur gear 19 will be rotated as the rack bar 23 is held stationary 15 by suitable clamping means connected with the frame 1.

In order to prevent the spur gear 19 from leaving the rack bar 23, a roller 24 is provided which rests on top of the rack bar and is rigidly clamped to the bracket 15 by a bolt 25. It will be noted from Figure 3 that the bolt 25 is provided with a shoulder and a nut, one of which may be clamped 20 rigidly in place and thereby permit the roller 24 to freely rotate. The pulley 12, spur gear 19 and associated parts are so proportioned that the extreme movement of the tube bar 2 caused by pin 3 for instance, will cause the plate 5' to move entirely across 25 the knitting machine whereas a movement of half its design distance will cause the plate to move half way across.

In some machines, instead of having one tube bar 2 as shown in Figure 1, two bars are provided arranged at an angle to each other and when the invention is to be applied to this kind of a machine the bracket 15' (Figure 7) is to be used whereby the two 30 bars similar to bar 2, may extend through the apertures 26 and 27. Aside from this change, the bracket 15' is identical with the bracket 15. In the drawing, the device has been shown as being applied vertically 35 but under some circumstances it may be arranged to operate in a horizontal plane without changing the construction or the function of the various parts.

In operation, the plates 5 and 5' reciprocate or move back and forth a certain distance when two strips of cloth are being knit. If only one strip of cloth is being knit, one of these plates and associated parts 40 are removed. As the machine continues to operate and shift the bar 2 back and forth, the brackets 15 will be shifted back and forth and, consequently, the spur gear or pinion 19 will be actuated, which in turn will actuate the pulley wheels 12 and 13 45 for shifting the cord 10 and the plate 5. By the provision of a small spur gear and a large pulley wheel and associated parts, a multiplying mechanism is produced whereby a short movement of bar 2 will cause 50 a large movement of the cord 10 and the

plate 5'. As the bar 23 is stationary when the brackets are moved by the movement of bar 2, the multiplying mechanism just described will function and will pull the plate 5' in either direction, according to the 55 direction of movement of the bar 2. This back and forth movement of the plates 5 continues as long as the machine is in operation.

What I claim is:—

1. An attachment for a knitting machine provided with a tube bar and two carrying plates, of a flexible member connected to said plates, and means for moving said flexible member so as to shift said plates to any 60 desired extent, said means including a multiplying mechanism operated through said tube bar and provided with a pair of winding members for said flexible member.

2. In a knitting machine provided with a 65 tube bar and a tube carrying plate mounted thereon, a flexible member for sliding said plate along said tube bar, a pair of pulleys for moving said flexible member, said pulleys being arranged on opposite sides of 70 the machine whereby said plate may be moved from one side of the machine to the other to knit a strip of cloth the full width of the knitting machine, and multiplying mechanism operated by said tube bar for 75 actuating said pulleys.

3. An attachment for a knitting machine formed with a tube bar and a tube plate slidingly mounted thereon comprising a ligament connected with said plate, a pair of 80 pulleys connected to the end of said ligament, said pulleys being rotatably mounted so as to wind the thread and thereby move the tube plate longitudinally of said tube bar, a pair of brackets rigidly secured to 85 said tube bar and moved thereby, said brackets carrying said pulleys, and multiplying mechanism connected with the frame of the knitting machine and with the pulleys whereby the rotation of the pulleys is multiplied when the brackets are moved by said 90 tube bar.

4. In an attachment of the character described, a cord for moving a tube plate, a pair of pulleys connected to the end of said 95 cord, a bracket for each pulley, a stationary rack extending across each bracket, a spur gear rigidly secured to each of said pulleys and meshing with said brackets, said spur gears being carried by said brackets whereby as the brackets are moved the spur gears 100 will be moved for rotating said pulleys and thereby moving said cord and tube plate.

5. In an attachment for knitting machines of the character described, a ligament adapted to be connected with a tube plate, a pulley connected to each end of said ligament, said pulleys being arranged on opposite 105 sides of the knitting machine, a bracket rigidly secured to the tube bar of the knit- 110

- ting machine and acting as supports for said pulleys, a spur gear carried by each pulley and a rack secured to said knitting machine and held stationary, said rack meshing with said spur gears whereby when said tube bar moves said brackets the pulleys will be rotated and by reason of the difference in size of the respective parts the movement of the tube bar will be multiplied.
6. In an attachment for knitting machines of the character described, a flexible member adapted to be connected with the tube plate of the knitting machine, a pair of brackets rigidly secured to the tube bar of said knitting machine, a shaft carried by each of said brackets, a pulley rotatably mounted on each of said shafts and secured to the flexible member so that the flexible member may be wound on either pulley according to the direction of rotation thereof, a spur gear 20 rotatably mounted on each of said shafts, said spur gears being rigidly secured to the respective pulleys, a stationary rack arranged with the teeth in mesh with the respective spur gears, and means for preventing the rack and spur gears from separating as the brackets are moved whereby the spur gears will be caused to rotate and will wind and unwind said flexible member as the brackets move back and forth.
- 10 6. In an attachment for knitting machines of the character described, a flexible member adapted to be connected with the tube plate of the knitting machine, a pair of brackets rigidly secured to the tube bar of said knitting machine, a shaft carried by each of said brackets, a pulley rotatably mounted on
- 15

MAX MAXIK.
